UNITED STATES PATENT OFFICE

168,615

ENVELOPE

Jerome Hyman, Houston, Tex., assignor to Rockmont Envelope Co., Denver, Colo., a corporation of Colorado

Application November 26, 1951, Serial No. 17,527

Term of patent 14 years

(Cl. D59—8)

To all whom it may concern:

Be it known that I, Jerome Hyman, a citizen of the United States, residing at Houston, county of Harris, and State of Texas, have invented a new, original, and ornamental Design for an Envelope, of which the following is a specification, reference being had to the accompanying drawing, forming part thereof.

In the drawing:

Fig. 1 is a developed plan view of the inside of an envelope embodying my design; and

Fig. 2 is a front elevational view of the envelope.

I claim:

The ornamental design for an envelope, as shown and described.

JEROME HYMAN.
